DESIGN FOR A SELF ILLUMINATED AND ILLUMINATING TRANSPARENT RO- TARY DISPLAY TABLE

Max Deutsch, Long Branch, N. J.

Application November 18, 1944, Serial No. 116,444

Term of patent 14 years

(Cl. D80—9)

To all whom it may concern:

Be it known that I, Max Deutsch, a citizen of the United States, residing at Long Branch, in the county of Monmouth and State of New Jersey, have invented a new, original, and ornamental Design for a Self Illuminated and Illuminating Transparent Rotary Display Table, of which the following is a specification, reference being had to the accompanying drawing forming part thereof.

Fig. 1 is an elevational view of a self illuminated and illuminating transparent rotary display table embodying my new design; and

Fig. 2 is a top plan view thereof.

I claim:

The ornamental design for a self illuminated and illuminating transparent rotary display table, substantially as shown.

MAX DEUTSCH.
